COMBINED PACKAGING AND SERVING TRAY

Karl Rune Persson, Halmstad, Sweden, assignor to
Bila Cup AB, Halmstad, Sweden

Filed May 1, 1972, Ser. No. 249,491

Claims priority, application Sweden Nov. 1, 1971

Term of patent 14 years

Int. Cl. D9—03

U.S. Cl. D9—185

FIG. 1

FIG. 2

FIG. 3

FIG. 4

FIG. 1 is a top plan view of a combined packaging and serving tray with the lid in open position showing my new design;

FIG. 2 is a side elevational view thereof;

FIG. 3 is a side elevational view showing the side opposite that seen in FIG. 4;

FIG. 4 is a front elevational view thereof;

FIG. 5 is a perspective view thereof; and

FIG. 6 is a perspective view thereof with the lid in closed position.

The stippling in the drawing indicates shading only. The back of the combined packaging and serving tray is substantially plain and unornamented.

I claim:

The ornamental design for a combined packaging and serving tray, as shown and described.
